UNITED STATES PATENT OFFICE.

JULIUS RITTER, JR., OF RACINE, WISCONSIN, ASSIGNOR TO HARTMANN TRUNK COMPANY, OF RACINE, WISCONSIN, A CORPORATION OF WISCONSIN.

TRUNK SHOE-BOX CONNECTION.

Application filed December 19, 1924. Serial No. 756,950.

This invention relates to improvements in trunk shoe box connections, more particularly adapted for connecting shoe boxes in wardrobe trunks.

5 Wardrobe trunks are now usually provided with shoe boxes for holding shoes. These boxes are usually positioned in the lower front portion of the wardrobe section of the trunk and are removably connected thereto. Said wardrobe sections are usually provided with metal reinforcing valance strips which also serve as drawer stops to hold the drawers of the drawer section of the trunk in closed position when 15 the trunk sections are in closed position.

It is one of the objects of the present invention to provide a shoe box connection which may be easily combined with the wardrobe section valance strips.

20 A further object of the invention is to provide a trunk shoe box connection for pivotally and removably attaching the lower portion of the shoe box to the valance members of the wardrobe section of the trunk.

25 A further object of the invention is to provide a trunk shoe box connection which may be so mounted within a wardrobe section that it can be easily swung to a position of convenient accessibility without detaching 30 the trunk from the trunk section.

A further object of the invention is to provide a trunk shoe box connection which will permit the shoe box being easily detached from the trunk sections when desired.

35 A further object of the invention is to provide a trunk shoe box connection which is of simple construction, is strong and durable, and is well adapted for the purpose 40 desired.

With the above and other objects in view, the invention consists of the improved trunk shoe box connection and its parts and combinations as set forth in the claims, and all 45 equivalents thereof.

In the accompanying drawing in which the same reference characters indicate the same parts in all of the views:

Fig. 1 is a section view taken on line 1—1 50 of Fig. 2 of the lower portion of the wardrobe section of a wardrobe trunk provided with the improved shoe box connection, the view also indicating by dotted lines the shoe box swung to its outer position; and

Fig. 2 is a front view of the parts shown 55 in Fig. 1.

Referring to the drawing, the numeral 5 indicates the wardrobe section of a wardrobe trunk, and 6 the shoe box positioned in the lower front portion thereof. The wardrobe section has mounted therein opposite side edge metal reinforcing angle strips 7 and the lower front parts of said strips are bent inwardly to form inward depressions 8 which are provided with vertically extending elongated openings 9. Said openings 9 extend through the flat portions 9' of the strips 7.

The shoe box 6 is of rectangular shape, and its lower opposite front corner portions 70 have mounted thereon brackets 10 which are formed with laterally extending arms 10' provided with upwardly and forwardly projecting hook portions 11 offset from the box 6. The brackets 10 engage the lower front 75 and side corner portions of the shoe box and the arms 10' offset the hook portions 11 laterally from the opposite lower side portions of the box to points approximately in vertical alinement with the strip slots 9, and the 80 parts as bent upwardly are in register with said slots. The hook portions 11 then extend forwardly through the slots and then downwardly in front of the strips 7 to support the box from the strips and with the 85 bottom of the box spaced from the bottom portion of the trunk section. As thus arranged the box may be pivotally swung out of the trunk to the dotted line position 90 shown in Fig. 1, or if desired the shoe box, when in upright position, may be raised slightly and then pushed inwardly to disengage the hook members from the slotted portions of the strips, and then by tilting the 95 box sidewise, it may be entirely removed from the trunk.

The upper portion of the shoe box may be locked to the strips in any manner desired to hold the shoe box in vertical position.

100 By spacing the shoe box from the bottom and opposite sides of the trunk section and by using the comparatively long hook arms which are somewhat flexible, any give of the trunk sections will not be transmitted to the shoe box, and said shoe box will be relieved of all strain incidental to travel.

105 From the foregoing description, it will be

seen that the trunk shoe box connection is of very simple construction, and is well adapted for the purpose described.

What I claim as my invention is:

- 5 1. The combination with a trunk section, outwardly faced strips positioned on opposite sides of the trunk section and having openings formed in the lower portions thereof, a shoe box within the trunk section, and brackets secured to the lower opposite portions of the shoe box and having projecting hook portions which extend outwardly through the openings to pivotally and removably support the shoe box in the 10 trunk section.
- 15 2. The combination with a trunk section, outwardly faced strips positioned on opposite sides of the trunk section and having recessed portions formed in the lower parts thereof and openings in said recessed portions, a shoe box within the trunk section, and brackets secured to the lower opposite side portions of the shoe box and having forwardly projecting hook portions which 20 extend outwardly through the strip openings to removably and pivotally connect the shoe box to the trunk section.
- 25 3. The combination with a trunk section, outwardly faced strips positioned on opposite sides of the trunk section and having recessed portions formed in the lower parts 30

thereof and elongated openings in said recessed portions, a shoe box within the trunk section, and brackets secured to the lower opposite side portions of the shoe box and 35 having laterally extending arms with upwardly and forwardly projecting hook portions which extend outwardly through the elongated openings to removably and pivotally connect the shoe box to the trunk 40 section.

4. The combination with a trunk section, outwardly faced strips positioned on opposite sides of the trunk section and having recessed portions formed in the lower parts 45 thereof and elongated openings in said recessed portions, a shoe box within the trunk section and between the strips, and brackets secured to the lower front corner portions of the box and having laterally extending 50 arms with upwardly and forwardly projecting hook portions which extend outwardly through the elongated openings to support the box in spaced position from the bottom portion of the trunk section, said hook and strip connection permitting the box to be swung outwardly from the trunk section or to be entirely removed therefrom.

In testimony whereof, I affix my signature.

JULIUS RITTER, Jr.
